UNITED STATES PATENT OFFICE.

OTTO PARKER HALLOCK, OF MATTITUCK, NEW YORK, ASSIGNOR TO MOSES V. LIDDELL,
OF BROOKLYN, NEW YORK.

WHEELED SCRAPER.

1,174,713.

Specification of Letters Patent. Patented Mar. 7, 1916.

Application filed June 12, 1912. Serial No. 703,214.

To all whom it may concern:

Be it known that I, OTTO P. HALLOCK, a citizen of the United States, and a resident of Mattituck, in the county of Suffolk and State of New York, have invented a new and Improved Wheeled Scraper, of which the following is a full, clear, and exact description.

This invention relates to excavating machinery and has particular reference to machines of this character adapted especially for excavating and conveying the excavated earth from the point of excavation to the place of deposit. While this machine is particularly adapted for road making purposes, it is to be understood that its use is by no means to be limited to any particular art.

Among the objects of the invention is to produce a machine of the nature set forth which is composed of the minimum number of parts in proportion to the adaptability of the same for easy and rapid manipulation.

The foregoing and other objects of the invention will hereinafter be more fully described and claimed, and illustrated in the drawings accompanying this specification in which like characters of reference indicate corresponding parts in all the views, and in which—

Figure 1 is a plan view partly in section; Fig. 2 is a side elevation showing the scoop in position for excavating; Fig. 3 is a longitudinal section showing the scoop in full lines in elevated position as when filled for transportation, and showing in dotted lines the position of the scoop when dumping; Fig. 4 is a vertical section in detail of the means for lifting the scoop and holding it in elevated position; Fig. 5 is a plan view of the same; Fig. 6 is a detail plan view of the means for holding the scoop in closed position; and Fig. 7 is a transverse detail of the same on the line 7—7 of Fig. 6.

Referring particularly to the drawings, I show at 10 a substantially horizontal frame of any suitable configuration and carried upon front and rear trucks 11 and 12.

The machine is adapted to be operated by horse or other power attached directly thereto in any suitable manner, but such power means not being any part of the present invention the same is not shown. It will be understood, however, that the driver or operator of the machine will occupy a position

preferably at 13 on the front portion of the frame.

The excavating portions of the machine comprise a scoop 14 mounted within the frame and adapted to be lowered into digging position as indicated in Fig. 2, and when the machine is propelled forwardly the scoop will become filled, the material gliding along the bottom of the scoop. The scoop is pivoted at 15 below and in front of its transverse center to a pair of arms 16 whose ends are pivotally mounted upon the axle 17 to which the rear wheels 12 are rigidly connected. Rigidly connected to the pair of arms 16 is a transverse guard 18, the general position of which is at right angles to the plane of the arms but whose upper portion is curved forwardly on an arc whose center coincides with the axis of the pivots 15. The rear end of the scoop, but for the guard, is open, but the form at the ends of the side members of the scoop is such that the said guard 18 constitutes a closure for the rear end of the scoop when in normal position, as it will be when being filled and during transportation.

When the scoop is in the digging position, the arms 16 will be lowered at their front ends so as to bring the cutting edge of the scoop into contact with the earth. When the scoop is filled I provide suitable means automatically operated by the rotation of the rear axle for hoisting it. To this end I provide a gear wheel 19 connected to the rear axle, and meshing with said gear wheel is another gear wheel 20 journaled loosely upon a countershaft 21 parallel to the axle 17. The hub 20' of the wheel 20 is provided with clutch teeth adapted to be engaged by a clutch member 22 splined to the shaft 21 and adapted to be moved longitudinally thereon by means of a lever 23 pivoted at 24 on a cross member of the frame. Said lever 23 is under the control of the operator through a rod 25 connected to a hand lever 26. When the lever 26 is moved rearwardly the clutch 22 will be brought into engagement with the teeth of the gear wheel 20 whereby the shaft 21 will be rotated from the rear axle 17 but in the opposite direction. At the ends of the shaft 21 are mounted a pair of drums 27 between which and the front ends of the arms 16 are flexible connections, such as chains or cables 28. Said connections are guided over

pulleys 29 carried by standards 30 on the intermediate portions of the frame 10. It will be understood, therefore, that while the machine is being propelled forwardly and becoming filled, a continued movement thereof will cause the loaded scoop to be hoisted by operation of the foregoing mechanism directly from the rear axle. This operation being substantially automatic, but for the 10 throwing of the clutch, it is preferable that means be employed to automatically throw out the clutch when the scoop is sufficiently elevated. I, therefore, provide on the rear surface of the guard 18 a cam 31 which, at 15 the proper time, will engage the arm 32 connected to the clutch lever 23 whereby said lever and clutch will be moved in the direction opposite to that before described. The clutch by this means being thrown out of 20 connection with the gear wheel 20, the rotation of the shaft 21 will stop, though the gear wheel 20 may continue in rotation. Connected to the shaft 21, however, is a ratchet wheel 32 with which coöperates a 25 pawl 33 by virtue of a spring 34 whereby the arms 16 are maintained in their elevated position until it is again desired to fill the scoop.

The scoop is maintained in its closed position with respect to the guard 18 by means of a lock carried preferably by the arms 16 and including a bolt 35 operating through the guard 18 into coöperation with a lug 36 carried by the scoop in any convenient place.

35 The bolt 35 is operatively connected to an arm 37 carried upon a rock shaft 38 which extends across and is journaled upon the arms 16 in bearings 39. This locking device is preferably duplicated on the opposite side 40 of the scoop. Each bolt 35 is normally projected forward by means of the spring 40 so as to engage beneath the lug 36 when the scoop is swung into normal position.

In order to dump the load from the scoop, 45 any suitable means may be provided to rock the shaft 38 so as to cause the arms 37 to withdraw the bolts 35 from beneath the lugs 36. To this end I provide an arm 41 extending at an angle from the rock shaft 38 and 50 which is adapted to be operated by a lug 42 connected to a rod 43 guided along the bottom of one of the frame rails and having its front end connected to a bell crank lever 44 adapted to be operated by the operator's 55 foot. When the arms 16 and scoop are in their elevated position, the outer end of the arm 41 will lie in the path of the lug 42, and while said arms are thus elevated, a downward push upon the lever 44 will unlatch the scoop allowing it to swing by gravity under the influence of its load into the position indicated in dotted lines in Fig. 3. The rear end of the scoop then being open, the load will be dumped. The downward swing 60 of the rear end of the scoop may be limited

by any convenient means. I accomplish this in a preferred manner as by one or more chains 45 on one or both sides of the scoop. The upper end of each chain is shown connected to the frame at 46 and to the scoop 70 at 47. From this construction it will appear that when it is desired to re-load the scoop the arms 16 and guard 18 together with the front end of the scoop are lowered, but the chains 45 will hold the rear end of the scoop 75 elevated, whereby the bolts 35 will be brought into interlocking engagement with the lugs 36.

The scoop is adapted to be lowered for the purpose just set forth by means of a hand lever 48 which, by means of a rod 49 connected to one end of a lever 50, will operate to release the pawl 33, the opposite end of said lever bearing against the extension 51 of said pawl. The removal of the pawl from the ratchet wheel 32 will permit the arms 16 and scoop to gravitate freely, but to prevent a too rapid drop I provide a brake 52 on the shaft 21 and a brake shoe 53 adapted to be brought into engagement with said brake 80 simultaneously with the operation of the lever 50 on the pawl, said lever 50 being arranged to operate directly upon the brake shoe which is pivoted preferably upon the same axis as the pawl. 85

The several parts of this machine may be made of any materials best suited for their several functions, and the relative sizes and proportions of the parts may be varied to a great extent without departing 90 from the spirit of the invention. It is to be understood, furthermore, that I do not wish to be limited with respect to details of construction except as may be required by the state of the art. 95

Having thus described my invention, what I claim as new and desire to secure by Letters Patent, is:

1. In a machine of the character set forth, a pair of arms, a frame to which the rear ends of said arms are pivotally related, a scoop pivoted at the front ends of said arms and adapted to swing on its pivots with relation to said arms, the rear end of the scoop being open, a guard rigidly mounted 100 upon said arms and adapted to close the rear end of said scoop in normal position, means to control the several independent movements of the arms and the scoop, said controlling means including spring-pressed 105 bolts carried by the arms and movable longitudinally thereof and beveled faced lugs secured rigidly to the scoop and coöperating with said bolts, and means to release 110 said bolts from the lugs, the releasing means including a rock shaft, cranks extending 115 from the rock shaft to the bolts, and means to rock the shaft. 120

2. In an excavating machine, the combination of a frame, a scoop, means including

a pair of clutch operated drums to elevate the scoop with respect to the frame, and means to automatically disconnect the elevating means when the scoop reaches a certain height, said disconnecting means comprising a bell crank lever mounted on said frame on a vertical pivot, one arm of the bell crank lever coöperating with said clutch, and a cam carried by the scoop and brought into operative connection with the other arm of the bell crank lever when the scoop is hoisted.

3. In an excavator, the combination of a frame, a pair of arms pivoted for movement vertically with respect to said frame, a guard rigidly carried by said arms, a scoop pivoted to the front ends of the arms and having an open rear end coöperating with said guard, means carried by the arms and extending through said guard to lock

the scoop closed, and means to release said locking means, said releasing means comprising a rod mounted along said frame and reciprocable therealong, a lug carried by said rod, a rock shaft pivoted transversely on said arms and connected to said lock, and an arm extending at an angle from said rock shaft and thence turned laterally whereby when the arms are elevated the free end of said arm is brought into alignment with said rod lug, substantially as set forth.

In testimony whereof I have signed my name to this specification in the presence of two subscribing witnesses.

OTTO PARKER HALLOCK.
